UNITED STATES PATENT OFFICE.

SAMUEL C. PANDOLFO, OF ST. CLOUD, MINNESOTA.

CHAIR.

1,406,888.

Specification of Letters Patent. Patented Feb. 14, 1922.

Application filed May 20, 1920. Serial No. 382,713.

To all whom it may concern:

Be it known that I, SAMUEL C. PANDOLFO, a citizen of the United States, and a resident of St. Cloud, in the county of Stearns and 5 State of Minnesota, have invented a certain new and useful Improvement in Chairs, of which the following is a description, reference being had to the accompanying drawings, which form a part of my specification. 10 My invention relates to a chair or seat intended to be entirely made of metal and formed so as to collapse or fold into compact form when not in use. The invention has for its object the provision of a chair or 15 seat which will be comparatively light in weight and at the same time possess the desired strength and rigidity.

My invention comprises a chair or seat provided with a back or support adapted to 20 fold parallel and into compact relation with the seat when the chair is collapsed or folded; while at the same time the back or support will have such pivotal relation with the seat proper that its position will be maintained while the chair is in "set up" position.

The purpose of my invention is to provide a chair entirely made of metal and adapted to various uses, as for example, for camping, as an auxiliary seat in automobiles; and other like uses; which uses, and the advantages of my improved chair will be readily comprehended from the following detailed description of the accompanying 35 drawings, wherein:

Figure 1 is a perspective view of my improved chair in "set up" position.

Figure 2 is a vertical sectional view of the chair in "set up" position.

40 Figure 3 is a vertical sectional view of my improved chair shown in collapsed or folded condition.

Figure 4 is a cross-sectional view, taken on the line 4-4 of Figure 3 looking in the direction of the arrows.

45 Figure 5 is a detail sectional view taken on the line 5-5 of Figure 2 looking in the direction of the arrows.

Figure 6 is a detail view in perspective 50 of one of the forwardly presented legs of the chair; a portion being broken away and shown in section.

In the particular exemplification of the invention, the seat 10, which is formed of 55 sheet metal, has three sides or marginal

edges thereof, namely the two sides and front of the seat, bent downwardly or flanged as shown at 11. This not only provides a finished appearance to the seat, but at the same time reinforces it and prevents 60 bending. A leg 12 is pivotally secured to the two side flanges 11 adjacent the ends thereof, namely at the point 13; while the lower ends of the legs 12, 12 are reenforced and maintained in spaced relation by a suitable tie-rod 14. The rod 14 may be provided with slightly reduced ends at the points where they pass through the legs so that the main portion of the rod 14 also acts as a spacing member to prevent movement 70 of the legs 12, 12 at their lower ends toward each other. The legs 12, 12 at a suitable point intermediate of their ends are provided with a cross-rod or member 15, the ends whereof are swaged or otherwise secured to the legs 12, 12 and this rod 15 constitutes a pivot, as well as connecting rod, for a pair of legs 16, 16. That is to say, the rod 15 secures the two pairs of legs together, but in such manner that they may have 80 rotative movement during the "setting up" or collapsing manipulation of the chair. The rod 15 where it passes through the legs 12 and 16 is preferably slightly reduced, as shown at 17 in Figure 4, in order that the shoulder formed thereby will maintain legs 16, 16 in spaced relation with each other; and these reduced portions of the rod 15 are preferably provided with small spacers or washers as at 18 arranged between each leg 90 12 and 16 so as to maintain a slight spaced relation between the legs, which enables a more easy manipulation or movement of the legs, while at the same time they will prevent such rubbing contact between the legs, 95 as would likely scratch or mar the latter.

The upper ends of the legs 16, 16 are connected together by a suitable brace rod 19, which is adapted to be engaged and held by a suitable clip or lip 20 formed integral with 100 the flange 11 at the front of the seat 10, as shown in Figure 2. The lip 20 is preferably bent slightly upward toward the bottom of the seat 10, at a point intermediate of its ends, in order to provide a restricted passage therebetween for the rod 19 and thereby prevent the accidental movement of rod 19 past the clip or lip 20 and therefore hold the legs 17 in distended or "set up" position. With the clip 20, like the seat 10 and flanges 110

11, formed of sheet metal, it will be understood that the clip 20 will possess sufficient resiliency to permit the rod 19 to be forced past the free end of the clip or lip and permit the latter to spring back to normal position.

The flange 11 at the front side of the seat 10 is cut away at both ends, as shown at 20', to an extent commensurate with the 10 thickness of both legs 12 and 16, in order that the seat 10 may fold into parallel relation with the legs 12 and 16 when the chair is collapsed into the condition shown in Figure 3. The legs 16, like the legs 12, 15 are also provided at their lower ends with a brace rod 21 secured thereto in a manner similar to rod 14 in order to maintain the proper spaced relation at the lower ends of legs 16; and this rod 21 is arranged to come 20 into a different horizontal plane from rod 14 when the chair is collapsed, so that the two rods will not interfere with a complete folding of the legs into parallel relation, see Figure 3. In order to permit such folding 25 relation of the legs, the legs 16, at a point adapted to register with rod 14, are each provided with a notch 22 adapted to receive the rod 14 of the legs 12 as shown in Figure 3. The lower ends of the legs 30 are preferably chamfered or rounded, as shown in Figures 1 and 2, in order that they may firmly rest on the floor and at the same time preventing marring of the floor. The pivots 13 at the upper ends of legs 35 12 also constitute pivotal points for the back 23 which consists of sheet metal preferably provided with an upper rounded edge, while the side edges are each provided with a right angularly disposed and tapered portion or flange 24 increasing in width toward the bottom of the back; the back being of such width as to permit the flanges to overlap the rear side of the seat 10 sufficiently to receive the pivot-forming rivets 13. The 40 back 23 is so pivoted that it extends somewhat beneath the seat 10; and the lower ends of the flanges 24 are bent inwardly as at 25 beneath the seat, see Figure 2, so as to extend substantially parallel with the 45 lower edge of the back. This bent portion 25 in turn has an upturned lip or projection as at 26 which is adapted to extend substantially parallel with and bear against the upper ends of legs 12 when the chair 50 is in "set up" position. The bent portions 25 may be formed by severing the lower ends of the flanges 24 from the main part of the back 23 so as to permit the severed portions to be bent inwardly at right angles to the flange 24; while the lips 26 may be formed by partially severing the portions 25 from the forward edges of the flanges 24. The portions 25 may be brazed, welded or otherwise secured to the lower edge of the 55 back 23 if desired; although where sheet

metal of proper thickness is employed, the lips 25 and 26 will have sufficient strength to obviate the necessity of welding the parts.

It is apparent from the construction shown and described that the back 23 will not only be held at proper inclination to the seat 10, but will be firmly maintained in raised position; while at the same time the back 23 is so secured that it may be folded forwardly and downwardly upon the 70 seat 10 into parallel relation therewith, as shown in Figure 3.

Instead of constructing the legs of bar metal as shown in the drawings, the legs may be constructed out of strips of sheet 80 metal bent longitudinally into channel or U-shape, as shown in the detail view in Figure 6. In order to prevent the legs having sharp lower ends or edges, the intermediate or curved portion of the strips may 85 be extended slightly beyond the channeled portion and this extended portion bent back between the sides of the channel as shown at 27 in Figure 6, thereby providing a closed end to the lower part of the legs and therefore a smooth surface which will prevent marring or scratching of the floor; and this lip or extension 27 may be brazed or welded in place if desired.

I have shown and described what I believe 95 to be the simplest form of my metal chair; but modifications may be made in certain details without departing from the spirit of the invention.

What I claim is:—

1. A chair of the class described, comprising a seat portion formed of sheet metal, three edges whereof are turned downwardly or flanged, with the turned edge at one end of the seat provided with an integral extension or lip disposed beneath the seat, a plurality of metallic legs arranged in pairs to extend in opposite diagonal directions, the legs of one pair being pivotally secured to the turned down edges at one end 100 of the seat and connected together intermediate of their ends by a tie-rod, the legs of the second pair being pivotally mounted at a point intermediate of their ends on said tie-rod so as to be disposed intermediate of 105 the legs of the first pair, the upper ends of the legs of the second pair being secured together by a cross-rod adapted to be engaged by said lip when the chair is in "set up" position and thereby hold the second pair of 110 legs in place, and a sheet metal back, two sides whereof are bent forwardly and adapted to overlap the sides of the seat, the two bent sides of the back being pivotally mounted on the pivots of the first mentioned pair 115 of legs to adapt the back to fold down onto the seat, with the lower ends of said bent sides of the back formed to extend beneath the rear end of the seat and have abutting relation with the upper ends of said first 120

legs to adapt the back to fold down onto the seat, with the lower ends of said bent sides of the back formed to extend beneath the rear end of the seat and have abutting relation with the upper ends of said first 130

mentioned pair of legs to support the back in raised position, the turned down edge of the seat provided with the integral lip being cut away to permit the seat and both pairs 5 of legs to fold into parallel relation when the chair is collapsed.

2. A chair of the class described, comprising a sheet metal seat, the marginal edges whereof are turned downwardly, metallic 10 legs arranged in pairs, the legs of one pair being pivotally secured to the turned down edges at the rear end of the seat, a cross-rod secured to said legs at an intermediate point, said cross-rod being shouldered at its ends 15 intermediate of said first mentioned legs, the legs of the second pair being pivotally mounted at a point intermediate of their ends on said cross-rod intermediate of its shoulders and the legs of the first pair where-

by the legs of the second pair are maintained 20 in spaced relation and permitted to swing vertically, the upper ends of the legs of the second pair being adapted to come into abutting relation with the turned down edge at the front of the seat, and a sheet metal back 25 having flanged sides pivotally mounted on the pivots of the legs of the first pair and to the outside of the rear end of the seat so as to permit the back to fold down onto the seat, while the turned down edge at the front 30 of the seat is notched to receive the legs of both pairs and permit the seat, back and both pairs of legs to fold into parallel relation with one another.
